US0D1110810S

(12) **United States Design Patent** (10) **Patent No.:** **US D1,110,810 S**
(45) **Date of Patent:** **** Feb. 3, 2026**

(54) **CRISPER BOX**

(71) Applicant: **Suzhou Cainiao Home Products Co., Ltd.**, Suzhou (CN)

(72) Inventor: **Quanan Feng**, Zhejiang (CN)

(**) Term: **15 Years**

(21) Appl. No.: **29/908,880**

(22) Filed: **Jan. 16, 2024**

(30) **Foreign Application Priority Data**

Nov. 9, 2023 (CN) 202330730413.5

(51) **LOC (15) Cl.** **09-07**
